COMBINED SHADE ROLLER AND CURTAIN POLE BRACKET

Filed Sept. 12, 1922

UNITED STATES PATENT OFFICE.

ALONZO E. PACKER, OF NEW PHILADELPHIA, OHIO.

COMBINED SHADE-ROLLER AND CURTAIN-POLE BRACKET.

Application filed September 12, 1922. Serial No. 587,661.

To all whom it may concern:

Be it known that I, ALONZO E. PACKER, a citizen of the United States, and residing at New Philadelphia, in the county of Tuscarawas and State of Ohio, have invented 5 certain new and useful Improvements in Combined Shade-Roller and Curtain-Pole Brackets, of which the following is a specification, such as will enable those skilled in the art to which it appertains to make and use the same.

This invention relates to brackets for supporting shade rollers, curtain poles and the like, and the object of the invention is to 15 provide devices of this class preferably composed of stamped sheet metal parts mounted together, in such manner as to permit of the adjustment of one of the parts of said devices; a further object being to provide 20 bracket devices of the class specified which may be mounted in connection with the window frame without the use of screws, nails or other attaching devices; and with these and other objects in view, the invention consists in bracket devices of the class and for 25 the purpose specified which are simple in construction, efficient in use, and which are constructed as hereinafter described and claimed.

30 The invention is fully disclosed in the following specification, of which the accompanying drawing forms a part, in which the separate parts of my improvement are designated by suitable reference characters in 35 each of the views and in which:—

Fig. 1 is a plan view of a part of a window frame showing two of my improved brackets mounted in connection therewith, with parts of the construction broken away and 40 illustrating the method of using said brackets.

Fig. 2 is a partial section on the line 2—2 of Fig. 1.

Fig. 3 is a face view of one corner portion 45 of a window frame, showing one of my improved brackets mounted in connection therewith; and,

Figs. 4 and 5 are perspective detail views 50 of two parts of my improved bracket, which I employ.

In Figs. 1, 2 and 3 of the drawing, I have shown for the purpose of illustrating one use of my improvement, a part of a window frame 10 in connection with which my improved brackets 11 are mounted.

55

Each of the brackets 11 are composed of three sheet metal stampings 12, 13 and 14. The part 12 is substantially disk-shaped in form as clearly shown in Fig. 3 and the central portion of which is pressed outwardly 60 as shown at 15 and the outwardly pressed portion is provided with an elongated and vertically arranged aperture 16, and said outwardly pressed portion forms on the inner face of the part 12 a chamber 17 and the part 12 is provided with an upwardly, backwardly and downwardly directed extension 18 and the downwardly directed portion is provided with teeth or projections 19 and the extension 18 forms a hanger by means of 65 which the part 12 may be mounted in connection with the transverse top plate 10^a of the window frame, as clearly shown in the drawing, by passing the extension 18 downwardly over the plate 10^a with the teeth or 70 projections 19 passing between the plate 10^a and the surrounding body of the window frame.

75

The part 13 is substantially T-shaped in form and comprises a cross-head 20 and a 80 projecting arm 21 arranged at right angles to the cross-head 20 and in one instance the arm 21 is provided with an aperture 22 as shown in Fig. 5 and in the other instance with a recess 23 as shown in Fig. 2 of the 85 drawing, and the aperture 21 and recess 23 on respective parts 13 are adapted to receive and support the shanks of a shade roller 24 as clearly shown in Fig. 1 of the drawing. The part 13 is connected with and supported by the part 12 by passing the cross-head 20 inwardly through the aperture 16 to place 90 said cross-head within the chamber 17 as clearly shown in Figs. 1, 2 and 3 of the drawing and it will be understood that the arm 21 of the part 13 extends outwardly 95 from the part 12.

90

The part 14 is substantially L-shaped in form and comprises a comparatively narrow arm 25 which is adapted to be passed 100

through apertures 26 in the opposite side walls of the outwardly pressed portion 15 and the arm 25 extends into the chamber 17 rearwardly of or in back of the cross-head 5 20 as clearly shown in Fig. 2 of the drawing. The other arm 27 of the part 14 is adapted to extend outwardly at right angles to the arm 25 and parallel to the arm 21 of the part 13 and is provided in the top edge 10 thereof with two semi-circular recesses 28 adapted to receive and support curtain poles 29 and 30 as clearly shown in Fig. 1 of the drawing. The arm 27 of the part 14 is reinforced and strengthened where it joins 15 the arm 25 by a downwardly directed enlarged V-shaped portion 31 as clearly shown in Fig. 4 of the drawing.

In the use of my improved brackets, it 20 will be understood that the parts 13 and 14 will be made up in lefts and rights and constitute a pair and in assembling the parts thereof, and mounting the same in position, the parts 13 are first mounted in connection with the parts 12 and after which 25 the parts 14 are mounted in connection with the parts 12 as hereinbefore set out and the separate brackets thus assembled are mounted in connection with the frame work of the window or the top plate 10^a 30 thereof, it being understood that the brackets are adjusted to the desired position to receive and support a shade roller 24 of predetermined length and the parts 14 are 35 adjustably mounted in the parts 12, or may be extended laterally in opposite directions to support curtain poles of the desired length.

With my improved device, it will be apparent that the marring or defacing of the 40 woodwork of a window frame or the like, is obviated and I provide a simple and yet strong and durable method of mounting shade rollers and curtain poles in connection with a window frame or other support and while I have shown certain details of construction for carrying my invention into effect and have illustrated a specific use of my invention, it will be understood that I am not necessarily limited 45 in these respects and various changes in and modifications of the construction herein shown and described may be made within the scope of the appended claims without departing from the spirit of my invention or sacrificing its advantages.

Having fully described my invention, what I claim as new and desire to secure by Letters Patent, is:—

1. A bracket device of the class described, 60 comprising three sheet metal parts, one of said parts being of unitary construction substantially disk-shaped in form and provided with an outwardly pressed portion forming a chamber opening outwardly 65 through the rear face thereof, said out-

wardly pressed portion being provided centrally thereof with an elongated aperture, the opposite side walls of said outwardly pressed portion being provided with other apertures, said part being provided with 70 an upwardly, backwardly and downwardly directed extension, by means of which the same may be mounted in connection with a suitable support, and the other parts of said bracket being detachably mounted in 75 connection with said first named part, one of said parts passing through the elongated aperture and the other through the second named apertures of the first mentioned part.

2. A bracket device of the class described, 80 comprising three sheet metal parts, one of said parts being of unitary construction substantially disk-shaped in form and provided with an outwardly pressed portion forming a chamber opening outwardly 85 through the rear face thereof, said outwardly pressed portion being apertured centrally thereof with an elongated aperture, the opposite side walls of said outwardly pressed portion being provided with other 90 apertures, said part being provided with an upwardly, backwardly and downwardly directed extension by means of which the same may be mounted in connection with a suitable support and another of said parts 95 being substantially T-shaped in form and being adapted to be passed through the elongated aperture of said first named part for detachably connecting said part with said first named part, said last named part 100 extending outwardly at right angles to the first named part and being provided with means for receiving and supporting the shanks of a shade roller.

3. A bracket device of the class described, 105 comprising three sheet metal parts, one of said parts being of unitary construction substantially disk-shaped in form and provided with an outwardly pressed portion forming a chamber opening outwardly 110 through the rear face thereof, said outwardly pressed portion being provided centrally thereof with an elongated aperture, the opposite side walls of said outwardly pressed portion being provided with other apertures, said part being provided with an upwardly, backwardly and downwardly directed extension by means of which the same may be mounted in connection with a suitable support and another of said parts 115 being substantially T-shaped in form and being adapted to be passed through the elongated aperture of said first named part for detachably connecting said part with said first named part, said last named part 120 extending outwardly at right angles to the first named part and being provided with means for receiving and supporting the shanks of a shade roller, and the other of said parts being substantially L-shaped 125

in form and adapted to be passed through the other apertures by said first named part and to extend at right angles to said first named part and provided with means for supporting a curtain pole or poles thereon.

In testimony that I claim the foregoing as my invention I have signed my name in

presence of the subscribing witnesses this 25th day of August 1922.

ALONZO E. PACKER.
